UNITED STATES PATENT OFFICE.

WILLIAM S. STAIR, OF NEW YORK, N. Y.

REFRIGERATING-MACHINE.

1,195,162.

Specification of Letters Patent. Patented Aug. 15, 1916.

Application filed April 14, 1915. Serial No. 21,275.

To all whom it may concern:

Be it known that I, WILLIAM S. STAIR, a citizen of the United States, and a resident of the city of New York, borough of Brooklyn, in the county of Kings and State of New York, have invented a new and Improved Refrigerating-Machine, of which the following is a full, clear, and exact description.

10 My invention relates to refrigerating machines of the rotary type; and has reference more particularly to the inclosed rotary type of machine in which the refrigerating medium and the lubricating medium are 15 adapted to mix and are separated by the centrifugal force generated by the machine.

An object of the invention is to provide 20 a simple and efficient refrigerating machine in which the refrigerating medium is separated from the lubricating medium before the refrigerating medium is liquefied.

A further object of the invention is to provide a refrigerating machine having revoluble separators, in which the flow of the 25 lubricant and the refrigerating medium are in opposite directions, and having baffles breaking up the flow and permitting a more perfect separation between the two media.

30 A still further object of the invention is to provide a refrigerating machine having a revoluble condenser, a portion of which is emerged, and which condenser is substantially surrounded by a dripping chamber, 35 about which chamber an air current is formed to accelerate the evaporation of the water film formed by the condenser of the dripping chamber.

Still another object of the invention is to 40 provide a refrigerating machine in which the connection between the evaporator and the liquefied refrigerating medium container is controlled by the centrifugal force generated by the machine.

45 With the above and other objects in view, the nature of which will more fully appear as the description proceeds, the invention consists in the novel construction, combination and arrangement of parts as herein 50 fully described, illustrated and claimed.

In the accompanying drawings, forming part of the application, similar characters

of reference indicate corresponding parts in all the views.

Figure 1 is an axial section through my 55 machine in inoperative position; Fig. 2 is a plan view thereof with the cover removed, certain parts being shown in section in a plane at right angles to the section plane of Fig. 1; Fig. 3 is a transverse section on line 3—3, Fig. 2; Fig. 4 is a transverse section on line 4—4, Fig. 2, the dotted lines illustrating the position of the counterweight when the machine is in action; Fig. 5 is an enlarged, longitudinal section 60 through the valve leading to the expansion chamber; and Fig. 6 is a perspective view of the weights for actuating the valve.

Before proceeding to a more detailed description of my invention it must be clearly 70 understood that the number of compressors and eliminators in the machine can be varied in accordance with the size of the machine and the capacity of the same.

Referring to the drawings, 7 represents 75 a shell formed of three sections 8, 9 and 10 united by bolts 11' or any other suitable means. The end section 8 of the shell has an exterior extension 11 co-axial therewith and forming a shaft for the shell. The end 80 section 10 has also an outwardly directed tubular extension 12 co-axial therewith and also forming a shaft for the shell. The extensions 11 and 12 are journaled in bearings 13 formed in the casing 14 for the shell, 85 and which casing is provided with a removable cover 15 whereby access may be had to the shell and parts associated therewith.

A counterweight 16 is suspended within the shell 7 on ball bearings 17 carried by 90 the sections 8 and 9 respectively. The axis of oscillation of the counterweight is in alignment with the axis of the shell. A cavity 18 is provided in the counterweight 16 forming a reservoir for lubricant. The 95 open end of the reservoir is closed by a cover 19 having a scoop 20 for collecting the lubricant held against the inner peripheral surface of the shell formed by the sections 8 and 9. The inner peripheral surface of 100 the shell formed by these two sections is made to converge toward the central part of the peripheral surface whereat an annular groove 21 is formed, and which groove

- registers with the scoop 20. It is self-evident that the centrifugal force will bring the lubricant into the groove 21, wherefrom the scoop 20 will direct it into the reservoir 18 through the opening 22 provided between the cover 19 and the edge of the reservoir 18. A strainer 23 is located at the opening 22 through which the lubricant has to pass before entering the reservoir 18, thus assuring a clean lubricant within the same.
- A pin 24 projects laterally from the counterweight 16 into the section 9 of the shell, said pin being rigid with the counterweight 16; but its axis is not in alinement with the axis of oscillation of the counterweight, consequently the pin 24 is eccentric with the bearings 17. The pin 24 has a bore 25 leading to a chamber 26 within the counterweight which communicates by a conduit 27 with the lubricant reservoir 18. In the inoperative position of the machine, as indicated in full lines in Fig. 4, the conduit 27 is above the level of the lubricant within the reservoir 18, therefore cutting off the supply of lubricant from the reservoir to the chamber 26. But when the machine is in operative position, as indicated in dotted lines in Fig. 4, the lubricant can freely flow through the chamber 26 of the counterweight. The bore 25 leads from the chamber 26 to the surface of the pin and also to the ball bearing 17 carried by the section 9 of the shell. A passage 28 connects the chamber 26 with the ball bearing 17 carried by the section 8 of the shell so that lubricant from the reservoir 18 is supplied to the ball bearings on which the counterweight revolves and to the pin 24 on which the connecting rods 29 of the compressors are mounted.
- The section 9 of the shell is provided with cylinders 30 each engaged by a piston 31 secured to a corresponding connecting rod by a wrist pin 32. Piston rings 33 are provided on each piston, also circular grooves 34, the latter communicating with a recess 35 of the piston where the wrist pin end of the connecting rod is located. The recesses 35 of the pistons communicate with the central opening of the section 9 into which the pin 24 projects. The lubricant passing through the pin 24 will lubricate the same and afterward will be thrown from the connecting rod 29 into the recesses 35 from where it is carried to the circular grooves 34 and, consequently, to the cylinder walls. Passages 36 establish communication between the central opening of the shell 7 with the surrounding openings leading to the chamber formed by the sections 8 and 9 which inclose the counterweight 16. These passages 36 are adapted to return to said chamber that portion of the lubricant which does not pass through the cylinder and prevents an excessive accumulation of lubricant

in the central opening where the pin 24 is located.

Each of the cylinders 30 is equipped with a discharge valve 37 constructed of a ring which forms a cage for ball valves which are held to their seats by centrifugal force and the condensing pressure against them during the suction stroke of the corresponding piston, said ball valves opening during the discharge stroke of the same. Passages 38 bring the discharge valves 37 into communication with the interior of the shell when the balls are off their seat and insure the return to the shell of all lubricant passing through the cylinder. Each of the cylinders 30 is provided with a false head 39 forming a seat for the suction valve 40 and carrying a relief valve 41. The valves 41, under excessive pressure in the high pressure side of the machine will establish communication with the low pressure side of the machine. The suction valve is in the shape of a centrally apertured disk maintained against its seat by centrifugal force and discharge pressure, and will uncover the ports 42 during the suction stroke of the corresponding piston, thus admitting vapors of the refrigerating medium to the corresponding cylinder through said ports and through the central opening in the disk.

The ports 42 of the false head are in communication with the tubular extension 12 of the shell by means of passages 43. Attached to the hollow shaft 12 is a casing 44 which carries an evaporating coil 45 inclosed in a suitable chamber 45' to be refrigerated. One end of said coil is in direct communication with the hollow shaft 12. The other end of the coil leads to the expansion chamber 46 formed within the casing 44. A valve 47 is held to its seat by a spring 48 abutting against aperured plug 48' and the condensing pressure in the chamber 51, said valve 47 separates said chamber 51 from the expansion chamber 46. Engaging the valve 47 is a spindle 49 which is displaced axially by pivotally mounted weights 50 under the action of the centrifugal force generated by the speed, whereby the valve 47 is opened and permits the flow of liquid refrigerating medium from the chamber 51 to the expansion chamber 46. Associated with the spindle 49 is a spring 52 the tension of which can be varied by means of a cap 53 and an adjustable pin 54 and thereby any desired opening of the valve 47 may be obtained for any predetermined speed of the apparatus, thus assuring a flow of liquid refrigerant to the evaporator in proportion to the displacement of the compressors. It will be noted that the condensing pressure tends to close the valve 47, consequently an increase in pressure will reduce the valve opening and a decrease in the condensing pressure will increase the valve opening, so

that under these conditions the flow of the liquid refrigerant will be unaffected by changes in the condensing pressures. The valve 47 in chamber 51 is preferably 5 screened to prevent any extraneous matter from lodging itself in the seat of the valve and thereby affecting the operating of the machine. It is self-evident that in lieu of the weight 50 for the control of the valve 10 any other suitable means, such as diaphragms for example, can be provided with substantially the same result.

A liquid refrigerant receiver 55 connects the chamber 51 with the section 10 of the shell. The said receiver is in the shape of a tubular member concentric with the tubular shaft 12. The receiver 55 communicates with one end of a condensing coil 56 by means of a passage 57 formed within the 20 section 10 of the shell. The other end of the coil 56 leads into a central recess 58 within the section 10 of the shell. Located within the said recess 58 is a baffle member 59 which is spaced uniformly from all the surfaces of the recess and forming therewith a sinuous passage 60. A similar sinuous passage 61 is formed by a second baffle member 62 projecting into said baffle member 59 from the central opening of the shell section 25 9. The two sinuous passages 60 and 61 are intercommunicating through an opening 63 provided in the axis of the baffle member 59 and through which the bolt connecting the two baffle members to the section 10 projects. 30

35 The sinuous passage 61 communicates also at its periphery by a lead 64 with one end of chambers 65 provided in the section 9 of the shell. The other end of the chamber communicates with the interior of the shell 40 by a lead 66. Located within each chamber 65 is a lubricant eliminator 67. Each eliminator has a plurality of baffle plates 68 of any suitable design for eliminating the lubricant from the refrigerating gases 45 turning from the compressors through the lead 66 toward the condensing coils 56.

Surrounding the condenser 56 and mounted to revolve therewith is a screen 69 which, with the condensing coil is partly immersed 50 in the cold water contained in the base of the condenser chamber 70 forming part of the casing 14. Positioned within the condenser chamber 70 above the water level and about the screen 69 is a screen 71 which has 55 protuberances on its inner peripheral surface from which the water drips on to the screen 69. Therefore the screen 71 constitutes the dripping chamber. The revolving screen 69 will throw the water against the screen 60 71 from where the same will drip back on to the screen 69. The finely divided spray of water formed on the screen is cooled by accelerated evaporation produced by a current of air created by a fan 72 which is as- 65 sociated with the section 10 of the shell.

The said fan is adapted to draw the air through the central opening 73 of the casing 14 and direct the same to the passages 74 over the screen 71 and through the screen 69. The air, after passing through the 70 screens, finally escapes through the condenser chamber 70 into the casing 14.

For charging the machine with the refrigerating medium, the expansion chamber is equipped with a valve 77 whereby the 75 said chamber may be placed into communication with a passage 78. The shell 7 is also equipped with a valve 79 which will place it into communication with a passage 80. Through the valve 79 a vacuum may 80 be effected throughout the entire apparatus and, therefore, the refrigerating medium introduced through valve 77. The valve 79 can also be used for introducing the lubricant into the shell 7. 85

The operation of my apparatus is as follows: Upon the machine acquiring a certain velocity, the valve 47 will be displaced by the weights 50 under the centrifugal force generated by the machine. Consequently, 90 the liquid refrigerating medium will enter from the receiver 55 to the evaporator 45 through the expansion chamber 46. Through the evaporating coils 45 the refrigerating medium will flow as a gas or vapor through 95 the tubular shaft 12 to the compressor. From the compressors it is discharged through passages 38 into the shell 7, from which it will pass through the leads 66 into the lubricant eliminators 67, thence through 100 leads 64 to the sinuous passages 60 and 61, the said sinuous passages 60 and 61 forming additional lubricant eliminators for the compressed vapors of refrigerant flowing to the condenser where the said gases are condensed to a liquid before entering the receiver 55. It will be noted that the flow of the refrigerating vapors or gases and the liquid within the tubular shaft 12 and the receiver 55 is in opposite directions and that 105 the vapors surround the liquid, consequently helping to maintain the refrigerating medium within the receiver in a liquid form. The counterweight and the reservoirs associated therewith do not revolve but assume 115 the position shown in dotted line in Fig. 4. In this position the lubricant reservoir supplies lubricant to the pin 24 and the ball bearings 17. The lubricant from the bearings returns directly to the shell, while the portion of the lubricant from the pin passes through the cylinders, as previously described, but all of the lubricant is returned to the reservoir. 120

It will be noted that the flow of the vapors through the lubricant eliminators is in a direction opposite to the flow of the lubricant, which, under the action of the centrifugal force, is driven toward the periphery of the shell, thus, the vapors of the refrig- 125 130 135

erating medium are separated from the lubricant, which is in liquid state, and thereby a more perfect separation between the two mediums is obtained, which separation is further facilitated by the baffles 68 provided within the eliminators 67.

Due to the low velocity of the gas within the shell after the same has been discharged from the compressors, a certain portion of the lubricant acquired by the gas is deposited directly into the shell; the balance passes with the vapors or gases of the refrigerating medium to the lubricant eliminators, from where the lubricant is returned by centrifugal force to the shell, the gas passing to the condenser, as previously described.

From the foregoing description, taken in connection with the accompanying drawings, the advantage of the construction and operation of the apparatus shown will be readily understood by those skilled in the art to which the invention pertains; and while I have described the principle of operation, together with the apparatus which I now consider to be the best embodiment thereof, I desire to have it understood that the apparatus shown is merely illustrative and that such changes may be made as are within the scope of the appended claims.

I claim:

1. A rotary refrigerating machine comprising a compressor, means for supplying lubricant to the compressor, a condenser associated with the compressor, and means, interposed between the compressor and condenser for eliminating liquid lubricant from the compressed vapors of refrigerant delivered by the compressor to the condenser.
2. A rotary refrigerating machine, comprising a shell mounted to rotate, a compressor associated with the shell, means within the shell for supplying lubricant to the moving parts, a condenser associated with the shell, and means interposed between the compressor and the condenser for eliminating liquid lubricant present in the compressed gases flowing from the compressor to the condenser.
3. In a rotary refrigerating machine, a revoluble shell, a compressor, means located within the shell for supplying lubricant to the moving parts, said compressor being adapted to deliver the compressed refrigerant vapors into the shell, means associated with the shell for directing the compressed vapor from the periphery of the shell toward the center thereof whereby the liquid lubricant present in the compressed vapors flowing toward the axis is forced toward the periphery of the shell, and means for returning the lubricant from the periphery of the shell to the means for supplying the lubricant to the moving parts.
4. In a rotary refrigerating machine, a

revoluble condenser, a screen inclosing the condenser and mounted to rotate therewith, said screen and condenser adapted to be immersed in water, a dripping chamber substantially encompassing said screen, and a fan for supplying air through the dripping chamber, substantially as and for the purpose set forth.

5. In a rotary refrigerating machine, a revoluble condenser partly immersed, a dripping chamber surrounding the same and adapted to receive the water from the revoluble condenser, and means for forcing air through the dripping chamber.

6. In a rotary refrigerating machine, a revoluble evaporator, a liquid refrigerant receiver associated therewith, and a valve controlling the flow from the receiver to the evaporator controlled by the velocity of the revoluble evaporator.

7. In a rotary refrigerating machine, an evaporator, a liquid refrigerant receiver, a valve controlling the flow from the receiver to the evaporator, centrifugal operable means controlling the operation of the valve, and adjustable means for varying the displacement of the valve, substantially as and for the purpose set forth.

8. In a rotary refrigerating machine, a revoluble evaporator, a liquid refrigerant receiver, a valve controlling the flow from the receiver to the evaporator, means operable by centrifugal force controlling the operation of the valve, and adjustable means for varying the displacement of the valve under the centrifugal force.

9. In a rotary refrigerating machine, a water tank, a revoluble condenser partly immersed therein, means for receiving the water from the revolving condenser and returning the same in a finely divided state to the water tank, and means for circulating air through said means, substantially as and for the purpose set forth.

10. In a rotary refrigerating machine, a compressor, means for supplying liquid lubricant to the compressor, a condenser associated with the compressor, and means, including baffles, interposed between the compressor and condenser for eliminating liquid lubricant from the compressed vapors of the refrigerant delivered by the compressor to the condenser.

11. In a rotary refrigerating machine, a revoluble shell, a compressor associated therewith, means located within the shell for supplying lubricant to the moving parts, said compressor being adapted to deliver the compressed refrigerant vapor into the shell, a condenser associated with the shell, means associated with the shell and condenser for directing the compressed vapors from the periphery of the shell through the center thereof into the condenser, baffle plates within said means for

- breaking up the flow so as to obtain a more perfect separation between the compressed refrigerant and liquid lubricant, said last mentioned means being adapted to return the lubricant to the shell at the periphery thereof, and means for scooping the lubricant from the periphery of the shell into the means for supplying the lubricant to the moving parts.
12. In a rotary refrigerating machine, a condenser, an evaporator, a revolute shell, a counterweight freely suspended within the shell, compressors associated with the shell and counterweight controlling the flow of the refrigerant from the condenser to the evaporator, said counterweight forming a lubricant reservoir adapted to supply lubricant to the movable parts within the shell, lubricant eliminators positioned within the shell intermediate the compressor and the condenser, and means for returning the lubricant eliminated from the refrigerant to the reservoir within the counterweight.
13. In a rotary refrigerating machine, a revolute evaporator, a revolute condenser, a revolute shell, a counterweight freely suspended within the shell, a compressor associated with the shell, a condenser communicating with said evaporator and shell, a liquid refrigerant receiver positioned between the condenser and evaporator, a valve controlling the flow from the receiver and the evaporator, centrifugal operable means controlling the operation of the valve, said counterweight forming a lubricant reservoir adapted to supply lubricant to the movable parts within the shell, lubricant eliminators positioned between the condenser and the shell wherethrough the compressed vapors discharged by the compressors into the shell are conveyed into the condenser and the lubricant returned to the shell, baffle plates in said eliminators, and means associated with the counterweight for scooping the lubricant from the shell into the counterweight.
14. In a refrigerating machine, a centrifugal separator comprising a chamber adapted to receive refrigerant in vapor form mixed with liquid lubricant, said chamber having an outlet for lubricant and an outlet for refrigerant, the latter outlet being nearer to the axis of rotation than the lubricant outlet, the centrifugal force causing the lubricant present in the refrigerating vapor to move toward the lubricant outlet as the refrigerating vapor moves to the refrigerant outlet, due to the greater density of the lubricant over the refrigerating vapor.
15. In a rotary refrigerating machine, a revolute separator comprising a chamber adapted to receive refrigerant in vapor form mixed with liquid lubricant, said chamber having a lubricant outlet and an outlet for refrigerant nearer to the axis of rotation than the lubricant outlet, and means for offering resistance to the flow of refrigerant from the refrigerant outlet to the lubricant outlet.
16. A rotary refrigerating machine, comprising a compressor, means for supplying lubricant to the compressor, a condenser associated with the compressor, and a centrifugal separator for eliminating liquid lubricant from the compressed vapors of refrigerant delivered by the compressor to the condenser.
17. A rotary refrigerating machine, comprising a compressor, means for supplying lubricant to the compressor, a condenser associated with the compressor, and means for centrifugally separating lubricant from compressed vapors of refrigerant delivered by the compressor to the condenser.
18. In a rotary refrigerating machine, a revolute shell, a compressor associated therewith, a lubricant container within the shell for supplying lubricant to the moving parts, a condenser associated with the central part of the shell, said compressor being adapted to discharge compressed refrigerant into the shell, and a separator for centrifugally eliminating liquid lubricant from the compressed vapor, said separator having a lubricant outlet at the periphery of the shell, and a refrigerating vapor outlet at the central part of the shell leading to the condenser.
19. In a rotary refrigerating machine, a revolute evaporator, a revolute condenser, a liquid refrigerant receiver between the condenser and the evaporator, a valve controlling the flow of the refrigerant from the receiver to the evaporator, weights associated with the valve and adapted to be moved apart by the centrifugal force, whereby the valve is operated, and adjustable means for varying the displacement of the weights whereby the displacement of the valve is controlled.
20. In a rotary refrigerating machine, a revolute shell, a suspended counterweight free to revolve and having a lubricant receptacle rendering said counterweight unbalanced whereby said weight is displaced angularly by the velocity of the shell, said receptacle having an inlet and an outlet which becomes operative when the counterweight is displaced angularly, and scooping means associated with the receptacle at the inlet for collecting the lubricant from the inner periphery of the shell and directing it into the inlet of the receptacle.
21. In a rotary refrigerating machine, a revolute shell, a counterweight suspended in the shell and free to revolve, said counterweight having a lubricant receptacle rendering the counterweight unbalanced, whereby the same is displaced angularly during the revolution of the shell, said re-

- ceptacle having a lubricant inlet and a lubricant outlet which becomes operative when the counterweight is displaced angularly and whereby lubricant is fed through 5 the outlet to the movable parts within the shell, said shell having a circular groove on the inner periphery thereof, a scooping member carried by the counterweight and located adjacent the inlet of the receptacle 10 and engaging said circular groove, and a strainer at the inlet of the receptacle adapted to receive the oil collected by the scooping member before the same passes into the receptacle.
- 15 22. In a refrigerating machine, a centrifugal separator comprising a chamber adapted to receive refrigerant in vapor form mixed with liquid lubricant, said chamber having an outlet for lubricant and an outlet 20 for refrigerant, the latter outlet being nearer to the axis of rotation than the lubricant outlet, and baffle plates across the chamber interposed between the outlets, the alternate plates having openings at the periphery of the chamber, the other plates having openings in the central part thereof.
- 25 23. In a rotary refrigerating machine, a revoluble separator comprising a cylindrical chamber, the axis of which is normal to the axis of rotation, said chamber being 30 adapted to receive refrigerant in vapor form mixed with liquid lubricant at the end of the chamber remote from the axis of rotation, said chamber having an outlet for lubricant at said end of the chamber remote from the axis of rotation, said chamber having a refrigerant outlet at the other end of the chamber, and concavo-convex baffle plates disposed across the chamber between 35 the outlets, the facing surfaces of the baffles being of the same character, the alternate plates having an opening in the central part thereof and the other plates having openings at the margin.
- 40 24. In a rotary refrigerating machine, a revoluble separator comprising an elongated chamber the longitudinal axis of which is normal to the axis of rotation of said separator, said chamber having an inlet for refrigerant in vapor form mixed with liquid lubricant at the end of the shell remote from the axis of rotation, said chamber having an outlet for refrigerant at said end of the chamber remote from the axis of rotation and an outlet for refrigerant at the other end of the chamber, and concavo-convex baffle plates extending across said chamber between the outlets, the adjacent baffle plates having the facing sides of the same 45 character, the alternate plates having openings at the margins thereof and the other plates, in central part.
- 50 25. In a rotary refrigerating machine, a revoluble shell, a condenser associated with the shell, a revoluble evaporator, a hollow shaft connecting the evaporator with the shell, a compressor within the shell operable by the movement thereof, said shell having means establishing communication between the hollow shaft and the compressor, said shell having also means for establishing communication between the condenser and the compressor, a tube within the hollow shaft connecting the shell to the evaporator, said shell having means establishing communication between said tube and condenser, and a valve controlling the flow from said tube to the evaporator.
- 55 26. In a rotary refrigerating machine, a revoluble shell, a coil-shaped condenser mounted to revolve with the shell, a casing, a hollow shaft connecting the casing to the shell to cause the same to revolve with the shell, a compressor within the shell operable by the movement thereof, said shell having means establishing communication between the hollow shaft and the compressor, said shell having also means establishing communication between the compressor and one end of the condenser, a tube within the shaft connecting the casing to the shell and mounted to revolve therewith, said shell having means establishing communication between the other end of the condenser and said tube, a coil-shaped evaporator mounted 60 about the casing and having both ends thereof secured to said casing, said casing having means establishing communication between one end of the coil and the hollow shaft, said casing having also means establishing communication between the other end of the coil and the tube, and a valve in said casing interposed between the said end of coil and said tube for controlling the flow from said tube to said evaporator.
- 65 27. In a rotary refrigerating machine, a revoluble shell, a compressor within the shell operable by the movement thereof, means for supplying lubricant to the compressor, an evaporator in communication with the compressor, a centrifugal separator for eliminating liquid lubricant from the compressed vapor of refrigerant delivered by the compressor, a condenser for receiving the refrigerant separated from the lubricant, and baffles within the shell interposed between the condenser and the separator.
- 70 28. In a rotary refrigerating machine, a revoluble shell, a compressor within the shell operable by the movement of the shell, means within the shell for supplying lubricant to the compressor, an evaporator exterior of the shell and mounted to revolve therewith in communication with the compressor, a centrifugal separator in the shell 75 mounted to revolve therewith adapted to receive from the compressor the vapors of refrigerant mixed with lubricant, a condenser connected to the shell and mounted to revolve therewith, said shell having 80

means establishing communication between the condenser and the separator, and cup-shaped, interengaging baffle members provided in the shell within the means establishing communication.

29. In a rotary refrigerating machine, a revolute shell, a compressor within the shell operable by the movement thereof, means within the shell for supplying lubricant to the moving parts, an evaporator in communication with the compressor through said shell, a valve controlling the communication between the evaporator and the compressor, a condenser in communication with the compressor through said shell, said valve controlling also the communication between the compressor and the condenser, and a relief valve associated with the compressor adapted to establish communication between the compressor and the separator independently of the first-mentioned valve.

30. In a rotary refrigerating machine, a revolute shell, a compressor within the shell operable by the movement thereof, an evaporator revolving with the shell, said shell having passages establishing communication between the compressor and evaporator, a valve controlling the communication, a condenser revolute with the shell, said shell having passages establishing communication between the condenser and the compressor, said valve controlling also the communication between the compressor and the condenser, and a relief valve adapted to establish communication between the compressor and the discharge leading from the compressor to the separator independently of the first-mentioned valve controlling the communication therebetween.

31. In a rotary refrigerating machine, a revolute shell having a radial bore, a piston in said bore, a counterweight within said shell, a connecting rod from the piston

to the counterweight, a head closing the end of the bore at the periphery of the shell, and a disk valve in said head for controlling the inlet to and the outlet from said bore at the periphery thereof.

32. In a rotary refrigerating machine, a revolute shell having a radial bore, a piston in said bore, a counterweight suspended within said shell, a rod connecting the piston to the counterweight whereby in the rotation of the shell the bore reciprocates on the piston, a head closing the end of the bore at the periphery of the shell, said head having an annular passage forming an inlet to the bore, said shell having passages leading to the head and constituting the outlet from the bore, and a disk valve for controlling the inlet and outlet from the bore, said disk valve having a central opening which is adapted to establish communication between the bore and the annular opening in the head, the margin of said disk valve controlling the openings leading from the shell to the head and constituting the outlet from the bore.

33. In a rotary refrigerating machine, a revolute shell having a radial bore, a piston in said bore, a counterweight mounted to oscillate within the shell in the axis of rotation of said shell, a crank pin in said counterweight eccentric with the axis of rotation, a rod connecting the piston to the crank pin, a head closing the end of the bore at the periphery of the shell, and a valve in said head for controlling the inlet to and the outlet from said bore.

In testimony whereof I have signed my name to this specification in the presence of two subscribing witnesses.
